(57) **CLAIM**

We claim the ornamental design for a chassis arrangement
for self-propelled agricultural machine, as shown and
described.

DESCRIPTION

FIG. 1 is a perspective view of a chassis arrangement for a
self-propelled agricultural machine showing our new design.
FIG. 2 is a right side view thereof.

FIG. 3 is a left side view thereof.

FIG. 4 is a front view thereof.

FIG. 5 is a rear view thereof; and,

FIG. 6 is a top view thereof.

The ornamental design which is claimed is shown in solid
lines in the drawings. Broken lines, if present in the draw-
ings, are for illustrative purposes only and form no part of
the claimed design.
